UNITED STATES PATENT OFFICE.

KARL GAMMEL, OF CLEVELAND, OHIO, ASSIGNOR TO THE CLEVELAND MACARONI COMPANY, OF CLEVELAND, OHIO, A CORPORATION OF OHIO.

MOLD FOR FORMING PASTES.

1,236,555.

Specification of Letters Patent. Patented Aug. 14, 1917.

Application filed August 19, 1911, Serial No. 645,025. Renewed January 6, 1917. Serial No. 141,058.

To all whom it may concern:

Be it known that I, KARL GAMMEL, a subject of the Emperor of Germany, residing at Cleveland, in the county of Cuyahoga and 5 State of Ohio, have invented certain new and useful Improvements in Molds for Forming Pastes, of which the following is a specification.

This invention relates particularly to improvements in the mold or die forming part 10 of a press, and the primary object of the invention is to provide means whereby the dough or paste, such as macaronic paste, may be heated sufficiently to cause same to 15 pass readily through the openings which may be provided in the mold or die.

A further object of the invention is to provide means whereby the mold or die may be heated uniformly so that all portions of 20 the mold or die will be at approximately the same temperature.

A further object of the invention is to provide means for supplying the heating fluid to the mold or die in such a way that 25 it can be readily removed from the press for the purpose of cleaning the same when desired.

The various other objects of the invention will be more fully set forth in the following 30 description of several forms of construction embodying my invention as set forth and claimed in the following specification.

Referring to the drawings forming a part 35 of this application,—

Figure 1 represents a plan view partly in section of a mold embodying my improvements.

Fig. 2 represents a partial cross-section on the line 2—2 of Fig. 1.

Fig. 3 is an enlarged detail sectional view 40 showing the construction of the inlet and outlet nozzles on the line 3—3 of Fig. 1.

Fig. 4 is a plan view of a modified form 45 of the mold or die.

Fig. 5 is a side elevation partly in section of the mold or die shown in Fig. 4.

The mold or die is preferably formed of 50 a plate 1 and a suitable ring 2. The periphery of the plate is channeled as at 3 so as to provide a passage for the heating fluid such as water or steam. Said annular channel communicates with an inlet 4 and an outlet 5 permitting circulation of the fluid.

The plate is provided with a plurality of 55 openings therethrough for the passage of

the paste, which are arranged in groups so as to leave parallel spaces between the groups. A central space 6 is provided with a passage 7 extending diametrically through the plate near the center thereof and smaller 60 passages 9 are arranged at right angles to the central passage and are formed in the spaces between the adjacent groups of openings communicating with said central passage 6 and with the annular passage 3.

Preferably two passages are provided in the smaller or transverse spaces, one being arranged near the top of the plate and the other being arranged near the bottom thereof.

The ring 2 may be secured to the plate in any desired manner. As shown in Fig. 2 the ring may be bolted to flanges 10 formed integral with the plate. It is obvious, however, that the ring may be soldered or welded in place as shown in Fig. 5.

In case only a single mold or die is used on the press table, the inlet and outlet nozzles 4 and 5 preferably communicate directly with the annular channel 3. Said 80 nozzles may be of any desired construction, which will insure a tight joint being made. In this construction preferably stops 12 are arranged in the annular passage, which cause the larger portion of the fluid to pass 85 through the central or main passage but permit a small quantity thereof to pass through the annular passage in at least one direction. In case a number of molds or dies are used in connection with a single 90 press, however, the inlets are preferably tapped into the bottom of the mold or die as shown in Fig. 5, and communicate directly with the central or main passage 7 which, in turn, communicates with the annular passage 3 through the openings provided therefor.

Preferably small openings 11 are arranged through the ring 2 opposite the central passage, which will enable same to be cleaned 100 and prevent clogging. These openings are normally plugged as shown.

In operation fluid is admitted through the inlet pipe and will circulate throughout all parts of the mold and finally leave the die 105 or mold through the outlet pipe. By this construction the mold is kept heated uniformly throughout practically its entire area, and consequently the dough or paste will pass with equal facility through all the 110

openings, which may be provided with pins or guides of any preferred construction.

Heretofore various attempts have been made to heat the presses, but in such cases the circulation of fluid has been around the outside of the press, thus leaving large portions of the area of the mold or die at a lower temperature. This caused that portion of the dough or paste adjacent to the heated portions to pass through the openings more readily than the dough or paste adjacent to the cooler portions, and thus caused the openings in such cooler portion to become clogged.

By my construction the dough or paste will pass evenly through all of the openings, thus preventing clogging and also permitting the output of the press to be increased at less expense, since less pressure is required when the dough or paste is partially heated.

I claim as my invention:

1. In a mold for forming pastes, a plate having a peripheral channel, a ring closing said channel to form a passage for a heating fluid, said plate having a main passage and smaller passages placing said main passage in fluid communication with said peripheral channel, an inlet and an outlet to said channel oppositely disposed to each other and to one side of said main passage, a stop having a restricted passageway therethrough for directing the fluid from said inlet through said peripheral channel and main passage, said plate having openings extending therethrough for the passage of the paste and surrounded by said channel and passages.

2. In a mold for forming pastes, a plate

having a plurality of openings extending therethrough for the passage of the paste, means for maintaining the paste in a heated condition while passing through said openings, said means including a plurality of connected passages in said plate surrounding said openings and positioned between the opposite ends of said openings, certain of said passages having open ends for facilitating circulation, means for feeding a heating fluid through said passages and a restriction in one of said passages to distribute the flow through the several passages.

3. In a mold for forming pastes, a plate having a peripheral channel, a ring closing said channel to form a passage for a heating fluid, said plate having a main passage and smaller passages placing said main passage in fluid communication with said peripheral channel, an inlet and an outlet to said channel oppositely disposed to each other, and to one side of said main passage, said ring having plugged openings in line with said main passage to facilitate cleaning the same, a stop having a restricted passageway therethrough for directing the fluid from said inlet through said peripheral channel and main passage, said plate having openings extending therethrough for the passage of the paste, and surrounded by said channel and passages.

This specification signed and witnessed this 4th day of August A. D., 1911.

KARL GAMMEL.
